*Primary Examiner—James R. Largen**Attorney, Agent, or Firm—Blum Kaplan*[57] **CLAIM**

The ornamental design for a sink web protector, as shown and described.

DESCRIPTION

FIG. 1 is a top, front and left side perspective view of a sink web protector showing my new design;

FIG. 2 is a left side elevational view thereof, the right side being the same as the left side;

FIG. 3 is a top plan view thereof;

FIG. 4 is a front elevational view thereof, the rear being the same as the front; and,

FIG. 5 is a bottom plan view thereof.
